UNITED STATES PATENT OFFICE.

MARSTIN DAVID GREENWOOD, OF HOOSICK FALLS, NEW YORK.

TOY PISTOL.

No. 920,565.

Specification of Letters Patent.

Patented May 4, 1909.

Application filed June 16, 1908. Serial No. 438,757.

To all whom it may concern:

Be it known that I, MARSTIN D. GREENWOOD, a citizen of the United States, and a resident of Hoosick Falls, in the county of 5 Rensselaer and State of New York, have invented a new and Improved Toy Pistol, of which the following is a full, clear, and exact description.

This invention relates to certain improvements in toy pistols, and more particularly, 10 to that type in which a resilient band is so arranged that when released, a projectile, such as a marble, a small stone or a bean, may be thrown.

One object of my invention is to hold the 15 projectile in the barrel of the pistol and adjacent the plunger while the pistol is being aimed and to release the projectile simultaneously with the release of the plunger.

A further object is to simplify the mechanism for holding and operating the plunger which drives the projectile.

Reference is to be had to the accompanying drawings, forming a part of this specification, 20 in which similar characters of reference indicate corresponding parts in all the figures, and in which—

Figure 1 is a longitudinal section through 25 a toy pistol constructed in accordance with my invention, the pistol being ready for firing; Fig. 2 is a longitudinal section similar to Fig. 1, but showing the parts as they appear after the discharge; and Fig. 3 is a top plan view, the parts being in the position indicated in Fig. 1.

In the specific construction illustrated in the accompanying drawings, I form the barrel of the pistol of a tube 10 of substantially uniform length and secured at its rear end to 30 a stock or grip 11. The grip is provided with a cylindrical plug or projection 12, adapted to extend into the rear end of the tube to close the same, and is also provided with an extension or projection 13, engaging 35 with the under side of the tube a short distance at the rear end to brace and reinforce the same. The tube forming the barrel is provided with a slot 14 extending along the top thereof, two oppositely disposed slots 15 40 in the sides thereof, and a slot or opening 16 in the lower side thereof. Within the barrel is a movable plunger 17 operated by a rubber band 18 extending through the side slots 15. The plunger is preferably provided with 45 an opening 19 extending transversely there- 50 through and of a width substantially equal

to the width of the slot 15 and the width of the rubber band, and from the opening 19 to the forward end of the plunger, the latter is cut away to form side grooves 20. At the 60 muzzle, a piece of wire is soldered to the under side of the barrel and extends upwardly to form two substantially parallel hooks or projections 21 upon opposite sides. The endless rubber band 18 is looped about 65 one of the projections 21, extends through one of the slots 15 in the barrel, through the opening 19 in the plunger, out through the opposite slot 15, and is looped about the opposite hook or projection 21.

For guiding the plunger and preventing any rotation thereof within the barrel, a guide in the form of a screw 22 is provided extending into the plunger intermediate its ends and extending up through the slot 14. 70 The head of this screw when the plunger is in the position indicated in Fig. 1, may constitute a sight.

Secured to the under side of the barrel and adapted to extend up through the slot or 80 opening 16, are two separate springs 23 and 24. The spring 24 is provided with an in-turned end 25, which is adapted to engage with the front end of the plunger and hold it in its rearward position with the band 18 85 stretched taut. Adjacent this spring is arranged a trigger 26 pivoted between lugs 27 carried by the barrel and having one end in engagement with the spring 25 adjacent its other end, so that by pulling on the trigger, 90 the projection 25 is moved out of the barrel and out of the path of the plunger to release the latter. The spring 23 has one end thereof secured to the barrel adjacent the front end thereof, and is provided with a projection 28 adapted to extend into the barrel at a short distance in advance of the projection 25. The terminal portion of the spring 23 lies adjacent the outer surface of the front end of the spring 24, so that when the last- 95 mentioned spring is pulled down to release the plunger, as indicated in Fig. 2, the spring 23 will also be pulled down and out of the barrel and out of the path of the plunger. The projection 25 of the spring 24 serves to 100 retain the plunger in position, as previously stated, while the projection 28 of the spring 23 serves to retain the projectile in position and adjacent the end of the plunger. The pulling of the trigger releases both the projectile and the plunger simultaneously. To facilitate the rearward movement of the 105 110

plunger against the action of the tension means 18, said plunger is preferably provided with a transverse bar 29 in the rear of the opening 19 and extending out through the 5 slots 15 of the barrel. The rear end of the plunger at its lower side is preferably cut away or inclined to depress the two springs in succession as the plunger is pulled backward, thus avoiding the necessity of depressing 10 the springs by the action of the trigger.

As will be noted, the rubber band constituting the tension means, extends freely through the opening 19 and grooves 20 of the plunger, and should it become worn or 15 broken, a new band may be very readily inserted without employing any tools or instruments, and without requiring the services of one particularly skilled.

The screw 22 serves not only to guide the 20 plunger and prevent rotation thereof and to limit the movement of said plunger, but also constitutes a sight. The stock or grip 11 serves not only to rigidly support the barrel but also serves to close the rear end thereof. 25 The pulling on the trigger releases the plunger and the projectile simultaneously, so that the piston may be employed in shooting downwardly as well as upwardly.

Having thus described my invention, I 30 claim as new and desire to secure by Letters Patent:

1. A toy pistol having a barrel, a plunger movable therein, a spring having a projection extending into said barrel and adapted 35 to retain the plunger adjacent the rear end of the barrel, a second spring having a projection extending into the barrel and adapted to retain a projectile adjacent the end of the plunger, means for withdrawing one of said 40 springs, and means whereby the withdrawing of said first-mentioned spring withdraws the other spring.

2. A toy pistol comprising a barrel having slots extending longitudinally thereof along

opposite sides, a plunger within said barrel 45 and having an opening therethrough, and grooves in the sides thereof extending from the opening to the front end of said plunger, hooks adjacent the muzzle of said barrel and upon opposite sides thereof, and an elastic 50 band extending from one of said hooks through the slots in the barrel and the opening in the plunger, into engagement with the opposite hook.

3. A toy pistol comprising a barrel having 55 slots in the opposite sides thereof, a slot in the upper side thereof, and a slot in the lower side thereof, means extending through the first-mentioned slots for reciprocating said plunger, a combined guide and stop extending through said top slot for limiting the movement of said plunger, and means extending through the bottom slot for retaining the plunger adjacent the rear end of the barrel and retaining a projectile adjacent 60 thereto.

4. A toy pistol, comprising a barrel, a plunger movable therein, a spring secured to the under side of said barrel and having a projection extending into said barrel and 70 adapted to retain the plunger adjacent the rear end of the barrel, a second spring having a projection extending into the barrel in front of the first-mentioned projection and adapted to retain a projectile adjacent the end of the plunger, one end of said second spring extending adjacent the first-mentioned spring, and means whereby the withdrawal of the first-mentioned spring withdraws the second-mentioned spring. 75

In testimony whereof I have signed my name to this specification in the presence of two subscribing witnesses.

MARSTIN DAVID GREENWOOD.
